VENTILATOR

Merton L. Fisk, Somerville, Mass.

Application May 21, 1937, Serial No. 143,956

4 Claims. (Cl. 98—99)

My invention relates to a device commonly designated as a ventilator adapted for installation at the inner side of a window sash. It is more closely related to that type arranged to direct a current of air upwardly as it enters the room; this type of ventilator is usually designed for angular adjustment relative to the sash whereby the air current may be controlled, both as to direction and volume.

10 This device is arranged to overcome several objections to the present day ventilator of the foregoing type. These objections reflect both the practical and commercial inefficiency of present day ventilators. I have perfected a device adapted to be received and held in position by the window frame screw, a unit common to frame structures. This eliminates extra attaching means and avoids mutilation of the window frame.

20 Another novel feature of my device is the ease with which it may be placed in operating position and also be restored to non-operating position without removal thereof from the supporting members. To the best of my knowledge, all 25 ventilators, of this type, comprise a frame adapted for lengthwise adjustment for windows of various widths; these frames usually contain glass, or metal, panels to function as a deflector of air currents and must be removed as a unit 30 from their supporting brackets when not needed, or whenever an unobstructed window area is desired; on such an occasion the operator is then confronted with the problem of where to place it for the time being, or for storage purposes, 35 as they are cumbersome and fragile. The foregoing difficulty is eliminated by my improved device wherein a flexible reflector unit is employed and can be automatically taken up on a roller element by merely freeing the outer end 40 of said deflector, the roller being constantly under spring tension in winding direction.

An outstanding defect in present day ventilators lies in the fact that they only partially shield the window stool and frame members in 45 stormy weather; my improved ventilator is arranged to prevent rain and snow from contacting these frame members but at the same time permit air to enter the room.

This improved ventilator is arranged for extremely simple adjustment to meet all conditions, easy installation and removal from the window frame, and to present a small package for display or storage purposes.

The invention will be best understood by the following description and drawings wherein one

embodiment will be disclosed and the scope thereof indicated by the appended claims.

In the drawings:

Figure 1 is a front elevation of my improved device in operative position relative to a window frame.

Fig. 2 illustrates the device in non-operative position but available for immediate use.

Fig. 3 is a vertical section on line 3—3 of Fig. 1.

Fig. 4 is illustrative of the protective qualities 10 presented by my device.

Fig. 5 is a plan view on line 5—5 of Fig. 1.

Fig. 6 is a plan section on line 6—6 of Fig. 2; and

Fig. 7 is a cross section on line 7—7 of Fig. 4. 15

Figure 1 illustrates the association of this invention relative to a conventional window frame comprising a stool 10, inside casing members 11, sash guide members 12 and 13, arranged to cooperate with a slidable sash unit 14, and the sill 15 with which the sash contacts when in closed position. The usual parting bead is shown at 16 and serves to maintain sash 14 relative to members 12 and 13 which, in turn, are held in position by a plurality of wood screws, the lower one of which is shown at 17, Figs. 3 and 4. It is a fact that this lower screw, 17, is universally used and located in substantially the same spot on all standard frames and I have taken advantage of this fact in the present case for two reasons; first, no attaching element need be furnished with the device; second, the casing need not be marred by additional holes to be exposed after removal of the supporting brackets.

In view of the foregoing I have provided a pair 35 of supporting brackets 18 and 19, positioned at the left and right sides, respectively, of the window frame as seen in Figs. 1 and 2. These brackets may be similar in outline, and each provided with an elongated slot 20 having an enlarged portion 21 at the lower end thereof adapted to be slipped over the head of screw 17, above referred to, after the latter has been slightly unscrewed to permit bracket 18 to be moved into position as clearly shown in Figs. 3 and 4; the screw may then be tightened to obtain a desired degree of friction between the bracket and window frame member; it will be understood that the brackets 18 and 19 may then be instantly adjusted, about screw 17 as a fulcrum, to vary their 40 angular position relative to sash 14.

The bracket 18 may be provided with a pair of outwardly extended flanges 22 and 23 at the upper and lower edges, respectively, thereof while their inner edges are preferably flanged, as at 24, 50 55

to prevent direct passage of air into the room. The upper flange 22 is provided with a notched aperture 25, Fig. 5, adapted to receive the outer end of a roller shaft 26 having a flattened portion to prevent rotation thereof in aperture 25. The shaft 26 may extend into a roller element 27, in axial alinement therewith, and connected thereto by means of a helical spring member 28, one end of which is connected to said shaft, the other end thereof being anchored in said roller, as shown in Fig. 6. This provides an arrangement whereby roller 27 may be constantly urged to rotate, under influence of the spring, in a clockwise direction as indicated by the arrows. The lower end of roller 27 is received by flange 23 and rotatably supported thereat by a screw member 29.

Wound about roller 27 I provide several turns of thin flexible material 30, such as water-proofed paper, or fabric, the number of turns embodying sufficient length to extend the width of a given window. The inner edge of this material may be secured to the roller in any suitable manner (not shown) while the outer edge thereof is preferably received by a stiffening, or binder element 31, of thin metal extending the entire width thereof. At a convenient point on the element 31 I provide an operating handle, or knob, 32 secured thereto by screw 33. This knob is arranged to present a neck portion 34 adapted to be received by an elongated slot 35 in the flange on bracket 19, as shown in Figs. 1 and 2.

Referring to Fig. 7, it will be noted that the side wall of the bracket lies in a plane with the outer edge of parting bead 16 and could therefore pass beyond said bead during angular adjustment of the bracket. I prefer that this should not happen and therefore provide a stop element 36 in the form of an elongated spring member, one end 40 of which is riveted, as at 37, to flange 24, the free end being allowed to protrude from an aperture 38 in the bracket and engage bead 16, as shown. When the bracket is adjusted to the position shown in Fig. 3 the element 36 will flex and assume a position flush with the bracket surface when engaged by guide member 12.

It will now be understood that after the knob 32 has been drawn to the right, Fig. 1, and dropped into slot 35, the strip of material 30 presents an air deflecting element similar to the conventional type employing glass, or other inflexible material. The spring 28 should remain under tension at all times, thereby holding the material taut when in operating position. It follows that upon releasing the knob, from slot 35, roller 27 will automatically wind the material 30 thereon until said knob engages flange 24 and arrests the action.

Referring to Figs. 3 and 4 it will be noted that angular adjustment of the brackets 18 and 19 may be accomplished by oscillating them about the screws 17 as a pivot point, said point being located about midway the length of said brackets. This arrangement permits a tilting action whereby the lower edge of material 30 may be positioned outside and below the edge of stool 10, as clearly shown in Fig. 4, thereby deflecting rain or snow away from said stool and protecting the same. It will be seen that the bracket becomes locked between stool 10 and bead 16, rendering the former rigid. Present-day ventilators of this type are pivoted at the extreme lower end of the bracket and therefore cannot be adjusted to offer such protection to the stool, hence the sash must

be closed in stormy weather, with the resulting loss of ventilation.

The present device presents a structure easily applied by the layman, quickly adjustable from operating to non-operating position without removal thereof from the window frame, and extremely compact for storage or handling purposes, bracket 19 being adapted for nesting with the left hand unit, all of which features are believed to be absent in conventional ventilators of this order. It is non-breakable, inexpensive to manufacture and requires no adjustment for differences in window widths.

I claim:

1. A device of the class described comprising an air-current deflector curtain spirally wound about a roller unit, a pair of brackets for supporting the deflector curtain, and individual means for pivotally mounting each bracket to a window frame part and relative to the stool, the pivot point being positioned a sufficient distance above the stool so as to permit unlimited tilting of the deflector curtain relative to the stool surface, for the purpose set forth.

2. A ventilator of the class described comprising, in combination, a bracket adapted for pivoted attachment to one side of a window structure, a second bracket also adapted for pivoted attachment to the opposite side of the window structure, an air-current deflector element positioned intermediate and supported by said brackets, and a yieldable stop member carried by each bracket arranged to engage its respective parting bead to limit pivotal movement of the bracket in one direction only.

3. In ventilating apparatus, the combination of an elongated strip of flexible material, a roller unit upon which the material is adapted to be wound when not in use but arranged to release said material at will for the purpose set forth, a supporting bracket adapted to receive the roller unit in a generally upstanding position, said bracket having an elongated slot therein adapted to receive a fastening member in a manner to permit rotation of the bracket thereabout, a stiffening member secured to the free edge of the flexible material, a second pivotally mounted bracket arranged to receive said stiffening member, each of said brackets being operable independently of the other to establish parallel relationship between the upper and lower edges of said flexible material.

4. In ventilating apparatus of the class described, an air-current deflector unit comprising a curtain element having the lower edge thereof normally positioned adjacent the window stool surface, a pair of elongated bracket members adapted to support the deflector unit in adjusted relationship with the window stool, said brackets being positioned, respectively, at each side of the window frame, individual attaching means associated with each of said brackets arranged to permit both oscillatory and lengthwise adjustment of the brackets relative to each other and the window frame, the lower end of each bracket being arranged to engage the outer edge of the window stool, and a retractable stop member carried by each bracket adapted to simultaneously engage a parting bead, whereby the brackets become locked against oscillatory movement in either direction.

MERTON L. FISK.
